United States Patent Office.

WILLIAM T. GILLINDER, OF PHILADELPHIA, PENNSYLVANIA.

Design No. 3,914, dated March 22, 1870.

DESIGN FOR ORNAMENTING GLASSWARE.

The Schedule referred to in these Letters Patent and making part of the same.

I, WILLIAM T. GILLINDER, of the city of Philadelphia, in the State of Pennsylvania, have invented and produced a new and original Design for the Ornamentation of Glassware, of which the following is a specification.

The nature of my design is fully represented in the accompanying drawing, to which reference is made.

It consists of stars *a a*, in *bas relief*, on a frosted surface, *b*, on the outside of the glass vessel, the stars being of clear smooth surfaces, and thus affording brilliancy in contrast with the frosted or semi-trans-

parent character of the general surface surrounding them.

Claim.

The design for the ornamentation of glassware, as shown.

WILLIAM T. GILLINDER.

Witnesses:

BENJ. MORISON,
WM. H. MORISON.
